(57) **CLAIM**

The ornamental design for a portion of a shoe, as shown and
described.

DESCRIPTION

FIG. 1 is a side elevational view of a portion of a shoe
showing our new design;

FIG. 2 is a side elevational view of a second embodiment
thereof;

FIG. 3 is a side elevational view of a third embodiment
thereof;

FIG. 4 is a side elevational view of a fourth embodiment
thereof; and,

FIG. 5 is a side elevational view of a fifth embodiment
thereof.

The broken line showing of portions of the shoe in Figures
1-5 is for illustrative purposes only, merely constituting a
disclosure, and forms no part of the claimed design. Patches
of shading indicate color for an entire section.
